UNITED STATES PATENT OFFICE.

HARRY N. GOLDSMITH, OF PHILADELPHIA, PENNSYLVANIA, ASSIGNOR TO GOLCO SANITARY SYSTEM, INC., OF PHILADELPHIA, PENNSYLVANIA, A CORPORATION OF DELAWARE.

COMBINED TILE STRUCTURE AND TOILET-PAPER HOLDER.

Application filed December 19, 1921. Serial No. 523,413.

To all whom it may concern:

Be it known that I, HARRY N. GOLDSMITH, a citizen of the United States, residing at Philadelphia, county of Philadelphia, and 5 State of Pennsylvania, have invented a new and useful Improvement in Combined Tile Structure and Toilet-Paper Holders, of which the following is a full, clear, and exact description, reference being had to the 10 accompanying drawings, which form a part of this specification.

My invention relates to an improvement in toilet paper containers adaptable for use in toilet rooms having tiled walls.

15 Heretofore various types of toilet paper containers have been applied to tiled walls either by the use of screws or other attaching means, or by insetting the container or its base into the wall after cutting away ad- 20 jacent tiles for its reception.

The use of screws or other attaching means is unsatisfactory since the containers are not securely held to the wall and the inset method of application is costly, because 25 of the necessity for cutting away the tiles for its reception, which takes considerable time, requires skilled labor, and results in loss due to damage to tiles in the cutting.

The object of my invention is to provide 30 a container which may be applied to a wall and become a part thereof without the use of attaching devices or the cutting of any of the tiles forming the wall, which container will receive support from the wall 35 without in any way marring or changing the continuity of arrangement of the tiles forming the wall.

Having now indicated in a general way 40 the nature, purpose and advantage of my invention, I will proceed to a detailed description thereof with reference to the accompanying drawings, in which I have illustrated several embodiments thereof and in which—

45 Fig. 1 is a perspective view of a toilet paper holder embodying my invention.

Fig. 2 is an elevation of a section of tile wall with the device shown in Fig. 1 in place.

Figs. 3, 5 and 7 are perspective views of 50 modifications of the device shown in Fig. 1.

Figs. 4, 6 and 8 are elevations of sections of tiled wall with the devices of Figs. 3, 5 and 7 respectively in place.

Referring to Figures 1 and 2, *d* represents 55 a tile wall structure, the tiles forming which are arranged in conventional pattern. *a* represents a container, within the confines of which a package of toilet paper is adapted to be held, there being a slot *b* in the front wall of the container through which the package of toilet paper is inserted and through which the individual sheets are withdrawn.

The rear wall of the container is thickened 65 and extended laterally to form the winged member *c*, which is so formed as to correspond in size and arrangement to two tiles in the wall structure *d*.

Referring to Figure 3, 4, 5 and 6; *d'* and 70 *d''* represent wall structures similar to that shown in Fig. 2, while *a'* and *a''* represent containers for toilet paper similar to the container *a* of Fig. 1. *c'* and *c''* indicate, respectively, winged structures formed by 75 thickening and laterally extending the rear wall of the container similar to the winged structure *c* in Figure 1. The winged structures *c'* and *c''* are, respectively, formed of a size to correspond to a single tile in the 80 walls *d'* and *d''* respectively. The tile *c'* is formed centrally of the rear wall of the container *a'*, while the tile *c''* is formed at the upper end of the rear wall of the container *a''*.

Referring to Figures 7 and 8; *d³* indicates 85 a wall structure similar to that shown in Figure 1, while *a³* represents a container for toilet paper having a slot *b³* in its front wall. The front wall of the container *a³* is extended in a vertical plane to form the winged structure *c³*, which is so formed as to correspond in size and arrangement to three tiles in the wall structure *d³*.

In the application of the embodiments of 95 my invention illustrated in Figures 1, 3 and 5, there are removed, or omitted, from the wall structure one or more tiles; one in

the case of the structure shown in Figures 3 and 5, and two in the case of the structure shown in Fig. 1. The winged structures c , c' or c^2 , as the case may be, are then substituted for the tiles or tile removed or omitted from the wall structures and cemented in place. The winged structures substituted for the tiles removed or used in place of the tiles become a part of and 10 serve the continuity of arrangement of the wall structure and serve to support the container, which overlaps the tiles adjacent to those removed, while tiles do not have to be cut or otherwise interfered with for the 15 accommodation of the container.

It will be obvious that in forming the winged structure on the containers c , c' and c^2 the rear of the container may be left open except for that part included in the 20 winged structures, thus saving the necessity for thickening the back wall, the winged structures being then formed by merely extending the back wall laterally. The open portions of the back are closed by tiles in 25 the wall structure when the container is in place.

The application of the structure illustrated in Figure 7 is similar to that of the structures of Figures 1, 3 and 5 except that 30 after the removal of three tiles from the wall structure a recess is cut in the wall for the reception of the container a^3 . The container is then set into the wall and the winged structure c^3 substituted for the three 35 tiles removed from the wall structure and cemented therein.

It will now be observed that by virtue of my invention the toilet paper container is applied to the wall structure in such a manner as to become a part thereof without destroying or interfering with the continuity of the tiles in the wall and without the 40 necessity for cutting or otherwise marring

any of the tiles in the wall for the accommodation of the container.

Having now fully described my invention, what I claim and desire to protect by Letters Patent is:

1. In a tile faced wall structure in which the tiles are laid in a prearranged order, a 50 box-like structure covering a space on the wall of greater area than the space covered by a single tile, and a tile connected to said box laid between other tiles of the wall whereby said box is supported, the tile on the box being of the proper shape and size to form a portion of a prearranged design formed by the tiles.

2. A box-like structure adapted to be supported from a tile covered wall, said box 60 having an opening in its front wall, a representation of a tile on one of the walls of the box whose area is less than the area of the box, so that when the box is placed in position in the wall, the representation of the tile together with other tiles will form a 65 prearranged design.

3. A box-like structure adapted to be supported from a tile covered wall, said box 70 having an opening in its front wall, a representation of a plurality of tiles on one of the walls of the box, any one of the representatives of a tile having an area which is less than the area of the box, while the combined area of said representation of tiles is 75 greater than the area of the box, the representation of the tiles on the box being of such a size and shape, that when the box is positioned in the wall the representations of tiles together with other tiles will form a 80 prearranged design.

In testimony of which invention, I have hereunto set my hand, at Philadelphia, Pa., on this 16th day of December, 1921.

HARRY N. GOLDSMITH.
